United States Patent

Des. 239,386

Patented Mar. 30, 1976

239,386

SPRAY APPLICATOR

Vera A. Slater, 6136 Golden Valley Road, Golden Valley, Minn. 55422, and Duane F. Lilja, 2410 Central Ave. NE, Coon Rapids, Minn. 55418

Filed May 27, 1975, Ser. No. 581,118

Term of patent 14 years

Int. Cl. D23—01

U.S. Cl. D23—17

FIG. 1 is a perspective view of a spray applicator showing our new design;

FIG. 2 is a front elevational view thereof;

FIG. 3 is an elevational view taken from the side opposite that shown in FIG. 1;

FIG. 4 is a rear elevational view thereof; and

FIG. 5 is a top plan view thereof.

We claim:

The ornamental design for a spray applicator, substantially as shown.
